UNITED STATES PATENT OFFICE.

WILLIAM A. PARKINSON, OF SYRACUSE, NEW YORK.

SHOE-LACE FASTENER.

SPECIFICATION forming part of Letters Patent No. 661,768, dated November 13, 1900.

Application filed March 22, 1900. Serial No. 9,701. (No model.)

To all whom it may concern:

Be it known that I, WILLIAM A. PARKINSON, a citizen of the United States, and a resident of Syracuse, in the county of Onondaga, 5 in the State of New York, have invented new and useful Improvements in Shoe-Lace Fasteners, of which the following, taken in connection with the accompanying drawings, is a full, clear, and exact description.

This invention relates to a device which is designed to be attached to the upper of a shoe to receive the ends of the lace and prevent the same from becoming untied.

The object of the invention is to provide a lace-fastener which can be readily attached to the shoe and shall be simple, strong, and durable in construction, also efficient in its operation, and at the same time inexpensive in its manufacture.

The invention consists, essentially, of a fastening device comprising a base-plate attached to the shoe or other article and provided with a fixed jaw, a movable member connected to said plate and provided with a jaw facing said fixed jaw and with projections, said projections and jaws receiving the lace and the movable member actuated by the draft of the lace, whereby said jaws are caused to grip the lace, as hereinafter more fully described, and set forth in the claims.

In the accompanying drawings, Figure 1 is a side view of a portion of a shoe, illustrating my improved lace-fastener. Fig. 2 is an enlarged detail face view of the fastener with its gripping-jaws closed. Fig. 3 is also a face view showing the jaws open and the lace removed. Fig. 4 is a vertical transverse section on line X X in Fig. 3 viewed toward the right. Fig. 5 is a sectional view on the same line viewed in the opposite direction; and Figs. 6 and 7 are detail face views of the base-plate and movable member, respectively.

Referring to the drawings, A denotes the base-plate, which may be of any suitable shape, preferably annular, and is formed at its edge with perforated ears a a, by which it is attached to the upper B of the shoe. On the face of said plate A and near the edge thereof is formed a fixed jaw b, which consists of a projection having a beveled face, and at the central portion of the face of

said plate is formed an upwardly-extending tongue c.

C denotes the movable member, which consists of a segmental bar which is formed at 55 its central portion with a downwardly-projecting ear d, entering between the aforesaid tongue c and the base-plate A, and through said parts passes a pin e, whereby said bar is pivoted to be turned on the plate. One end 60 portion of said pivoted bar C is formed with a downwardly-hooked projection f, and the other end portion thereof is bent outwardly, thus forming a jaw g, and terminates with a downwardly-extending hook h, said latter jaw 65 having its face parallel to and facing the aforesaid fixed jaw b on the base-plate, and at the central portion of the bar C is formed an upwardly-hooked projection i.

D represents the shoe-lace, which is applied 70 to the shoe in the usual and well-known manner, and after the same has been tied the ends are drawn tightly under the downwardly-hooked projection f and then over the upwardly-hooked projection i. The lace is then 75 passed under the hook h and between the jaws g and b. When the lace is thus engaged, the draft of said lace on the projections f and i turns the pivoted bar C, whereby its jaw g is brought into engagement with 80 the fixed jaw b, and thus the lace is gripped and securely fastened.

While my described device is particularly adapted for fastening shoe-laces, yet it will be observed that by constructing the same on 85 a larger scale it can be used for a great many purposes where ropes and cords are employed and are required to be held securely.

What I claim as my invention is—

1. In a lace-fastener for shoes and analogous articles, the combination with a base-plate attached to the article and provided with a fixed jaw, a member pivoted on said plate and provided with a jaw facing the fixed jaw and with hooked projections, the lace engaging 90 said projections and passing between said jaws, and by its draft actuating said pivoted member to cause the jaws to grip the lace substantially as set forth.

2. In a lace-fastener for shoes and analogous articles, the combination with a base-plate attached to the article and formed on 100

its face with a fixed jaw, a segmental bar pivoted to said plate and formed at one end with a jaw facing the fixed jaw and with hooked projections, the lace engaging said projections and passing between said jaws, and by its draft actuating said bar to cause said jaws to grip the lace substantially as set forth.

3. In a lace-fastener for shoes and analogous articles, the combination with a base-
10 plate attached to the article and formed on its face with an inclined fixed jaw, a segmental bar pivoted to said plate and formed at one end with a corresponding jaw facing the fixed jaw, and at its other end with a down-
15 wardly-hooked projection, and at its intermediate portion with an upwardly-hooked projection, the lace engaging said projections and passing between said jaws and by its draft actuating said bar to cause the jaws to grip
20 the lace substantially as set forth.

4. In a lace-fastener for shoes and analogous articles, the combination with a base-
plate attached to the article and formed on its face with an inclined fixed jaw and with
25 a tongue rising therefrom, a segmental bar formed at its central portion with an ear by which it is pivoted between said tongue and

plate, one end of said bar being formed with a jaw corresponding to and facing the afore-
30 said fixed jaw and at its other end with a downwardly-hooked projection, and at its central portion with an upwardly-hooked projection, the lace engaging said projections and passing between said jaws and by its draft actuating said bar to cause said jaws to grip
35 the lace substantially as set forth.

5. In a lace-fastener for shoes and analogous articles, the combination with a base-
40 plate attached to the article and formed on its face with a fixed jaw, a segmental bar pivoted to said plate and formed at one end portion with a jaw facing the fixed jaw and terminating with a downwardly-extending hook, the other end portion of said bar being formed with a similar hook and the central portion 45 formed with an upwardly-extending hook, the lace engaging said hooks and passing between said jaws and by its draft actuating said bar to cause the jaws to grip the lace substantially as set forth.
